UNITED STATES PATENT OFFICE.

GEORGE P. BOSWORTH, OF CENTRAL FALLS, RHODE ISLAND, ASSIGNEE, BY MESNE ASSIGNMENTS, TO HEMPHILL COMPANY, OF CENTRAL FALLS, RHODE ISLAND, A CORPORATION OF MASSACHUSETTS.

CIRCULAR STOCKING MACHINE.

1,423,177.

Specification of Letters Patent. Patented July 18, 1922.

Application filed June 4, 1914, Serial No. 843,062. Renewed December 19, 1917. Serial No. 207,982.

To all whom it may concern:

Be it known that I, GEORGE P. BOSWORTH, citizen of the United States, residing at Central Falls, Rhode Island, have invented 5 certain new and useful Improvements in Circular Stocking Machines, of which the following is a specification.

In circular stocking knitting machines of the general type like the Banner made under 10 the patent of Hemphill, No. 933,443, September 7, 1909, a pair of narrowing and a pair of widening picks are employed, the former acting to elevate needles one by one from the columns of active needles to inoperative 15 position to narrow the fabric for the heel and toe pockets and the widening picks serving to lower two needles at each picking action; one of which, however, is subsequently raised by the narrowing picks, resulting 20 in widening the fabric by one needle at each reciprocating stroke of the knitting head. In the Banner machine the two narrowing picks are located at the right hand side of the knitting head, one at the front and one 25 at the rear, and the widening picks are located at the left of the knitting head one at the front and one at the rear. In some modifications of this type of machine the knitting head is set differently in relation to the 30 frame, so that the narrowing picks are located at the rear of the knitting head and the widening picks at the front thereof instead of at the right and left sides, respectively, of the knitting head, but in all such 35 machines the order of picking is the same.

In the Banner machine the narrowing picks for convenience may be referred to as the front and rear narrowing picks, and the widening picks may be likewise designated, 40 and the order of picking as heretofore practiced is beginning the picking for narrowing on the rear pick, and terminating the narrowing on the front pick, while in widening the rear widening pick begins the picking 45 and the widening picking terminates on this pick. This order of picking is objectionable, because at the termination of the widening there are less widening loops than narrowing loops, and where the heel is made of a 50 different color from the leg and foot the extra stitches in the narrowings are visible, and make the design irregular and lacking in symmetry, whereas at the toe a more serious objection exists in that there are less

widening stitches for looping than in the instep course, and in looping to close the toe a pucker appears in the fabric. 55

In order to avoid this objection I have provided a construction which will alter the order of picking, and while I have shown 60 this in connection with a machine organized like that disclosed in the patent of Hemphill, the invention may be organized for use in connection with machines of other makes than that of the Banner. 65

In the accompanying drawings—

Figure 1 is a view of the left hand end of a Banner machine looking from the left of Figure 3 of the Hemphill patent, the view being in the nature of a diagram, some parts 70 being omitted and some parts illustrated in dotted lines;

Figure 2 is a diagrammatic plan view of a needle cylinder with the picks located as in the Banner machine, though as above described the invention may be carried out in connection with machines of other types in which the relation of picks to the cylinder is not the same; 75

Figure 3 is a side view of the speed changing cam of the Banner machine with one part of my improvement combined therewith; 80

Figure 4 is a diagram showing the toe of the stocking in end view and the instep course in edge view before the toe is closed. 85

The reference characters used herein with few exceptions are the same as those designating corresponding parts in the Hemphill patent. 90

In these drawings, 1 is the rotating needle cylinder, *a*, *a'* the front and rear narrowing picks, and *b*, *b'* the front and rear widening picks. 95

In round knitting the needle cylinder rotates in the direction of the arrow *X*, opposite clockwise.

The drawing Figure 1 shows the parts at the middle of the heel with the widenings about to begin. 100

The narrowing has been just finished. The widening picks *b*, *b'* are down between the two planes of needles, the butts of the active needles being shown at *c* and the butts of the elevated inoperative needles 105 being shown at *d*, this position of the widening picks being their inoperative position.

The cylinder for round knitting is driven

22

through a train of gearing, of which train the bevel gears n , n' form a part, this gear train being similar to that shown in the Hemphill patent. For reciprocating knitting the cylinder is driven through the gears n' , n (and it may be noted here that gear n' meshes with the gear n on its far side in Fig. 1) the gear i'' on the shaft s and the segmental gear or toothed quadrant i^s . This quadrant is oscillated constantly, but only communicates motion to the cylinder through the gear i'' when the latter is clutched to the shaft as in the Hemphill patent, and this takes place when the machine goes on reciprocating knitting. The clutch is thrown, during the last part of the forward stroke of the segment, to change the drive, in fact in the Banner machine as organized heretofore all changes in the machine due to pattern mechanism take place on the forward stroke of the quadrant in the arrow direction y , because the pattern drum, as hereinafter referred to, is moved by a pawl on the quadrant operating the pattern drum on said forward stroke.

Therefore, in prior practice as the quadrant is moving forward or in the direction of the arrow y , the widening picks are raised to operative position so that as the quadrant goes back and the needle cylinder goes on its first reverse widening stroke, i. e., in the direction opposite to the arrow X , the widening pick b' having been raised will be in position to pick down the first two elevated or inoperative needles for beginning the widening of the fabric. This is due in ordinary prior practice to the pawl h^s freely pivoted to the quadrant at 6 engaging the tooth 8 of the ratchet wheel e fixed on the shaft s' to which the cam G' is fixed, which cam controls the position of the widening picks to be elevated into operation or lowered to inoperative position. The turning of the ratchet e therefore has heretofore caused the tooth 2 of the widening pick cam G' to pass under and lift the lever k which, through the rod k^2 , rod or pin k^4 , lifts the pick controller k^6 the arms of which overlie the stems of the picks so that when the controller lifts, the springs 12 , $12'$, shown in the Hemphill patent will raise the picks to their operative plane, and picking will begin on the rear widening pick b' when the quadrant i^s goes leftward or back and the needle cylinder rotates the reverse of the arrow direction X . In this lifting action the front pick will remain under the butts of the elevated needles till all have passed; when it will fly up by the action of its spring into operative plane to pick when the needle cylinder is on its other stroke, i. e., in the arrow direction X . My improvement consists in beginning the widening picks on the front pick b instead of the rear pick b' , as in prior practice, and for this purpose I provide a second tooth $8'$ in advance of the tooth 8 on the ratchet wheel e and I so control the pawl h^s that on its stroke to the right above described which, in prior practice, through the tooth 8 would have moved the cam G' sufficiently to lift, the widening picks will skip, in my present arrangement, the tooth 8 and engage the tooth $8'$, with the result that the cam G' will be turned only a part of its ordinary step and not sufficient to cause its high part or tooth 2 to raise the lever k , with the result that this movement will be an idle one, so far as the lifting of the widening picks to operative position is concerned. However, this short movement of the ratchet e will have the effect of turning the cam shaft s' so that a projection or tooth A connected with this shaft will be moved in the arrow direction, and this will, at the end of this short movement, get into the range of movement of a dog B' fixed on the far end (Fig. 1) of the shaft i^s upon which the quadrant i^s is fixed, so that as the quadrant moves leftward the dog B' will now engage the tooth A and turn the shaft s' sufficiently to make the high point 2 on the pick controlling cam G' pass to a position under the forward end of lever k , raising it, together with the pick controller k^6 , and allowing the widening picks to lift to their operative position through the action of their springs. This movement of the shaft s' by the dog B' and tooth A therefore completes a movement, together with the movement derived, from the tooth $8'$ equal to that which is ordinarily given by the pawl h^s acting on the tooth 8 , so that at the end the pick controlling cam G' is in the same position that it would be under prior practice when the pawl h^s engaged the tooth 8 and gave the full movement, but the termination of the movement with my improvement takes place on the back or leftward stroke of the quadrant instead of, as in prior practice, taking place on the forward movement of said quadrant with the result that when the widening picks are raised it is at the end of the cylinder stroke opposite to the arrow direction X ; consequently on the next stroke of the cylinder in the arrow direction the front pick b will be up and the first widening picking action will take place here. Whereas in prior practice as above stated as the forward movement of the quadrant and pawl h^s results in a complete step movement of the cam G' , the picks are lifted and the rear pick will be the first to act on the next change of cylinder stroke, or when it returns in the direction opposite to that of the arrow X , this being what my invention avoids.

Under my improvement one stroke of the cylinder, i. e., in the direction opposite to that of the arrow, is idle so far as picking for widening is concerned, but on the next

stroke picking begins, i. e., when the cylinder is moving in the arrow direction.

While the projection or tooth A may be variously arranged, I prefer to fix it on the speed changing cam p^6 shown fixed to the right hand end of the pattern shaft s' in Fig. 3 of the Hemphill patent, and when so located the dog B' will be located preferably at the right of the machine on an extension 10 of the shaft i^* to which the quadrant is fixed. I have shown in Fig. 3 a view of the dog B' and the speed changing cam p^6 looking from the opposite side of Fig. 1 indicating that the said parts are on the far side 15 of the machine as viewed in Figure 1. The pawl h^8 , as in the Hemphill patent, is controlled as to its engaging the teeth of the ratchet e by a controller h pivoted at h^3 to the frame, and having a tail piece h^7 upon 20 which the forward end of the pawl bears and slides. The controller is spring-pressed normally downwardly at its front end by the spring z , and has a lug h^4 to be engaged by lugs on the pattern chain B, one of these 25 lugs, a low one, being indicated in dotted lines at 1^* as having lifted the controller high enough at its front end that its tail piece will expose the half tooth $8'$ but shield the regular tooth 8 so that, as the pawl 30 comes forward it will, by riding on the tail of the controller, miss the tooth 8 and engage only the tooth $8'$, thus moving the cam G' only a part of its regular step and not enough to effect the raising of the widening 35 picks. In this manner the pawl h^8 is controlled. At certain other times the controller will be lifted by the higher projections 1^a to allow the pawl to engage the teeth of the ratchet e .

40 The pattern chain B is operated step by step by a ratchet wheel c of the Hemphill patent, said ratchet being fixed to the sprocket wheel or drum about which the chain passes and this ratchet is operated by a pawl i^4 loosely hung on the rocking quadrant arm i^5 . This pawl rides on a fixed projection fixed to the frame which holds it in proper position to engage the ratchet c . The quadrant i^5 is operated from a face wheel i^6 45 through a link i^2 , the face wheel being driven from the gear i loose on the shaft s , and driven through a train of gears i^{10} , i^9 , i^7 , not shown herein but shown in Figure 3 of the Hemphill patent.

50 The action above described for widening at the heel is duplicated at the toe, the half tooth being shown at 8^a taking the place of the regular tooth in ordinary practice, which would reach from 8^b to 8^c , and the projection which cooperates with the dog B' to 55 kick the pattern drum forward in the direction of the arrow w on the back stroke of the quadrant being shown at A' . The uneven picking action is even more objectionable at the toe than at the heel, because of

the necessity of looping to close up the opening at the toe, the extra winding stitches causing the fabric to be puckered where these extra stitches occur.

In Figure 4 the toe narrowings are indicated at t and the widenings at t' . It will be seen that widening loops are lacking at the point t^2 to match with loops in the instep course u , and consequently when looping is done a pucker will appear at the point t^2 .

Old sequence of picking.

It may be mentioned here that the reciprocating strokes of the cylinder are through an arc slightly less than a complete revolution, for instance from E in the arrow direction around to E' and reverse.

Referring to the diagram Fig. 2, we will suppose we have four needles up at each end of the row of short butt needles, these occupying with their butts the same plane with the butts of the elevated long butt needles, and we will suppose we are to proceed with the widening as under prior practice. The four needles mentioned will be up when the machine has completed one of its reciprocating strokes in the arrow X direction or forward. The reverse rotation now takes place resulting in raising a needle at D on the rear narrowing pick, making five elevated needles here, and picking down two needles at E on the rear widening pick. On the next forward stroke one needle will be picked up at E on the front narrowing pick a and two needles will be picked down at D on the front widening pick. On the next reverse stroke one needle will be picked up at D on the rear narrowing pick, and two needles will be picked down at E on the rear widening pick.

On the next forward stroke one needle will be picked up at E on front narrowing pick and two needles will be picked down at D on front widening pick.

On the next reverse stroke a needle will be raised at D on the rear narrowing and two needles will be picked down at E on the rear widening pick, leaving three needles at D elevated and all down at E.

On the next forward stroke a needle will be raised at E on the front narrowing pick, and the widening picks and instep cam F will now be lowered, and this cam will lower the three needles at D, all the long butts and the one remaining short butt at E, and the machine continues in this forward direction for round knitting.

Improved sequence of picking.

I will now refer to my improved sequence of picking. Suppose four needles up at E and D: On the first reverse stroke, i. e., opposite the arrow direction, one needle goes up at D on the rear narrowing pick; no

needle goes down at E because the rear widening pick, contrary to prior practice, is now down in inoperative position. On this reverse stroke the dog B' operates the picker

5 cam G' to raise the widening picks. This, however, takes place at the end of the stroke after the needles at E have passed the widening picks.

On the next forward stroke one narrowing needle comes up at E on front narrowing pick, and two down at D on front widening pick.

10 On next reverse stroke, one needle comes up at D on rear narrowing pick and two down at E on rear widening pick.

15 On next forward stroke one needle comes up at E on front narrowing pick and two down at D on front widening pick.

20 On the next reverse stroke one needle is raised at D on the rear narrowing pick and two needles are lowered at E on the rear widening pick.

25 On the next forward stroke one needle is raised at E on the front narrowing pick and two are lowered at D on front widening pick.

30 On the next reverse movement one needle is raised at D on the rear narrowing pick and two are lowered at E on the rear widening pick.

35 On the next forward movement one up at E on front narrowing pick and two down at D on front widening pick; these two needles being all which are elevated at this point.

40 On the next reverse movement one needle is raised at D on the rear narrowing pick and two are lowered at E on the rear widening pick.

45 On the next forward movement which is now continued for round knitting, one needle comes up at E on the front narrowing pick, making one needle up at each side of the machine.

50 The instep lowering cam is now lowered and also the widening picks, and also the long butt needles, together with the two remaining elevated short butt needles, one at E and the other at D.

55 It will be understood that the terms "front" and "rear" as applied to the picks, and "forward" and "reverse" strokes as applied to the direction of motion of the needle cylinder are relative terms in the sense that they refer not necessarily to the actual location of these parts in relation to the front of the machine or the point where the operator stands, but rather to the direction of motion of the cylinder for continuous and reciprocating knitting, the terms "forward 60 stroke" being used to designate a movement of the cylinder in the same direction as in round knitting, the front widening pick being that one towards which the cylinder rotates from the point of location of the other widening pick, the front narrowing pick be-

ing substantially diametrically opposite the rear widening pick, and the rear narrowing pick being substantially diametrically opposite the front widening pick.

65 In view of the above it will be understood that the terms "front" and "rear" as applied to the picks and "forward" and "reverse" as applied to the strokes are used herein for convenience of identification, the invention not being limited to any particular 70 location of the picks in relation to what may be considered the front of the machine because of the position occupied by the attendant in running the machine.

75 I show at F the ordinary instep cam for elevating the long butt instep needles to inoperative position, this cam, as in usual practice, being raised to elevate these needles when the machine goes on reciprocating knitting.

80 I claim as my invention:—

1. In combination in a circular knitting machine, a needle cylinder, with means for rotating it continuously forward in one direction for round knitting, means for giving a rotary reciprocating movement to the said cylinder, narrowing picks, widening picks, a pattern drum having a cam for controlling the widening picks, and means for operating said cam to adjust the widening 95 picks to operative position, said means acting on the reverse stroke of the needle cylinder, substantially as described.

90 2. In combination in a circular stocking knitting machine, a continuous rotary and reciprocating needle cylinder, narrowing picks, widening picks, a pattern drum, a quadrant having oscillatory movement for reciprocating the needle cylinder, said pattern drum having cam means thereon for 100 controlling the position of the widening picks, means for operating said drum from the quadrant for adjusting the widening picks to operative position, said operation taking place on the reverse stroke of the 110 said quadrant and moving the pattern drum forwardly, substantially as described.

105 3. In combination in a circular stocking knitting machine, a continuous rotary and reciprocating needle cylinder, narrowing 115 picks, widening picks, a pattern drum having cam means for adjusting the widening picks to and from operative position, a quadrant for giving the needle cylinder its forward and reverse movements as said 120 quadrant moves respectively forward and backward, means for operating the pattern drum one step on the forward movement of the quadrant and another step on the reverse movement of the quadrant, the step 125 taking place on the reverse movement serving to move the widening picks to operative position, substantially as described.

4. In combination in a circular stocking knitting machine, a continuous rotary and 130

- reciprocating needle cylinder, narrowing and widening picks, a pattern drum, a quadrant for moving the needle cylinder forwardly on its forward stroke and rearwardly on its rearward stroke, said pattern drum being operated constantly in one direction, means for operating said drum from the quadrant on both its forward and reverse movements, said pattern drum having a pick operating cam for moving the widening picks to operative position on the reverse stroke of the quadrant and needle cylinder, substantially as described.
5. In combination in a circular stocking knitting machine, a continuous rotary and reciprocating needle cylinder, narrowing and widening picks, a pattern drum having a widening pick adjusting cam and operating in one direction step by step, a quadrant for reciprocating the needle cylinder, and connections from the quadrant to the pattern drum for moving it one step for each stroke of the quadrant, said pick cam adjusting the widening picks to operative position on the stroke of the quadrant corresponding to the reverse stroke of the needle cylinder, substantially as described.
6. In combination in a circular stocking knitting machine, a needle cylinder having continuous rotation for round knitting and reciprocating movement for heel and toe work, narrowing and widening picks, a pattern drum moving in one direction step by step, said pattern drum including a cam controlling the position of the widening picks, an oscillating quadrant for giving the needle cylinder its reciprocatory movement, a pawl for moving the pattern drum forwardly one step on one movement of the quadrant, and a dog connected with the quadrant and a tooth connected with the pattern drum for moving the said drum another step forward on the other stroke of the quadrant, said tooth being brought into range of said dog by the forward step of the drum first mentioned, substantially as described.
7. In combination in a circular stocking knitting machine, a needle cylinder having continuous rotation for round knitting and reciprocating movement for heel and toe work, narrowing and widening picks, a pattern drum moving in one direction step by step, said pattern drum including a cam controlling the position of the widening picks, an oscillating quadrant for giving the needle cylinder its reciprocatory movement, a pawl for moving the pattern drum forwardly one step on one movement of the quadrant, and a dog connected with the quadrant and a tooth connected with the pattern drum for moving the said drum another step forward on the other stroke of the quadrant, said tooth being brought into range of said dog by the forward step of the 65 drum first mentioned, said dog being connected with the shaft of the quadrant, substantially as described.
8. In combination in a circular stocking knitting machine, a needle cylinder having continuous rotation for round knitting and reciprocating movement for heel and toe work, narrowing and widening picks, a pattern drum moving in one direction step by step, said pattern drum including a cam 70 controlling the position of the widening picks, an oscillating quadrant for giving the needle cylinder its reciprocatory movement, a pawl for moving the pattern drum forwardly one step on one movement of the 75 quadrant, and a dog connected with the quadrant and a tooth connected with the pattern drum for moving the said drum another step forward on the other stroke of the quadrant, said tooth being brought into range of said dog by the forward step of the drum first mentioned, said dog being fixed on the shaft of the quadrant and said tooth being on the speed changing cam, substantially as described.
9. In combination in a circular stocking knitting machine, a needle cylinder having continuous rotation for round knitting and reciprocating movement for heel and toe work, narrowing and widening picks, a pattern drum having a cam for controlling the widening picks, a quadrant for reciprocating the cylinder, a ratchet wheel connected with the pattern drum, a pawl on the quadrant for engaging said ratchet, said ratchet having one of its teeth divided, a controller for the pawl, a pattern chain having means to set the controller to permit the pawl to give the ratchet a full step movement or to permit it to move the ratchet a half step on one of its strokes, and a dog connected with the quadrant and a tooth connected with the pattern drum to move the ratchet on the other stroke of the quadrant, substantially as described.
10. In a circular knitting machine, a continuous rotary and reciprocating needle cylinder, a pair of narrowing picks, a pair of widening picks, each of said widening picks lowering two needles on each widening operation and each of said narrowing picks raising one needle at each narrowing operation, and means for controlling the pick of the needles to begin the widening on one widening pick, and terminate the widening 105 on the other widening pick.
11. In a circular knitting machine, a continuous rotary and reciprocating needle cylinder, a pair of narrowing picks, a pair of widening picks, each of said widening picks 110 lowering two needles at each widening operation and each of said narrowing picks raising one needle at each narrowing operation,

- and means for controlling the picking operations to begin narrowing at one pick, to begin widening at the diametrically opposite pick, and to terminate the picking operations on the remaining picks. 5
12. In a circular knitting machine, a continuous rotary and reciprocating needle cylinder, a pair of narrowing picks, a pair of widening picks, each of said widening picks 10 lowering two needles, at each widening operation and each of said narrowing picks raising one needle at each narrowing operation, and means for controlling the picks to begin narrowing actions on one narrowing pick 15 and terminate picking upon the other narrowing pick, to begin widening on the widening pick diametrically opposite the narrowing pick first acting and to terminate the widening on the pick diametrically opposite the narrowing pick last in action. 20
13. In combination, in a knitting machine, a needle cylinder, a stitch cam, means relatively to rotate and oscillate said cam with respect to said needle cylinder, a narrowing 25 pick, a widening pick, a pattern drum having a cam for controlling the widening pick, and means for operating said cam to adjust the widening pick to operative position, said means acting upon the reverse stroke of the 30 needle cylinder.
14. In combination, in a knitting machine, a needle cylinder, a stitch cam, means relatively to rotate and oscillate said cam with respect to the needle cylinder, narrowing 35 picks, widening picks, a pattern drum having a cam for controlling the widening picks, and means for operating said cam to adjust the widening picks into operative
- position, said means acting on the reverse stroke of the needle cylinder. 40
15. In combination, in a knitting machine, a needle cylinder, a stitch cam, means relatively to rotate and oscillate said cam with respect to said needle cylinder, a narrowing pick, a widening pick, a pattern drum, and 45 means for positively moving said widening pick therefrom to render said pick operative, said means acting upon the reverse stroke of the needle cylinder. 50
16. In a knitting machine, a needle cylinder, a cam shaft, means to rotate and oscillate the needle cylinder, said means including an oscillated sector, a self-controlled narrowing picker, a widening picker, and means to throw said widening picker into 60 action, said means comprising a part operated by said sector upon its backward stroke. 65
17. In combination, in a circular hosiery knitting machine, a needle cylinder, a knitting cam carrier, means to rotate and to oscillate said needle cylinder with respect to said knitting cam carrier in the knitting of the leg, heel, foot and toe of the stocking or hose, a narrowing pick, a widening pick, a pattern member, and connections for positively moving said widening picker from said pattern member to render said pick operative, said connections acting upon the reverse stroke of the needle cylinder. 70
- In testimony whereof, I affix my signature 75 in presence of two witnesses.
